HYDRAULIC SYSTEM

Carroll R. Alden, Detroit, Mich., assignor to Ex-Cell-O Corporation, Detroit, Mich., a corporation of Michigan

Application October 11, 1943, Serial No. 505,799

12 Claims. (Cl. 60—52)

1

The invention pertains to improvements in hydraulic systems, and more particularly to a novel control arrangement for the same.

One object of the invention is to provide in a hydraulic system having high and low pressure sides, a novel arrangement for maintaining the high pressure side of the system either under a predetermined relatively high pressure or, alternatively, dropping the same to a low value, as may be desired.

More specifically, it is an object of the invention to provide in a hydraulic system embodying a pump as a source of pressure fluid and a main control valve for controlling the flow of fluid to a main actuator, a novel arrangement for optionally maintaining the pump discharge under substantial pressure or not, as may be desired, when the main control valve is shifted to its neutral or "off" position.

The optional maintenance of pump discharge under predetermined pressure or at substantially low pressure when the main actuator is stopped very substantially enhances the efficiency and potential fields of use of the system under different operating conditions. In the event that the pump is being used not only as a source of fluid pressure for a main actuator, but also as such source for some auxiliary device or other actuator, it is requisite that the pump output pressure be maintained if continued use of the auxiliary device is to be possible during those intervals during which the main actuator is stopped. On the other hand, mere maintenance of pump output pressure at all times, irrespective of system demand, is inexpedient and highly inefficient because of the frequent waste of power input for the pump which results. The present invention comprehends the use of a simple selector for conditioning the system either for pressure maintenance or not, just as may be desired, during the "off" periods of the main actuator.

A more specific object of the invention is to provide a hydraulic system in which a pressure operated diverting or governor valve is arranged not only to divert pump discharge in accordance with the pressure drop across a restricted orifice in the actuator exhaust line during normal operation of the actuator, but in which the governor valve may also be conditioned at will to divert fluid in the course of maintenance of a predetermined discharge pressure for the pump while the actuator is stopped.

Another object is to provide in a system employing a governor valve operable as noted in the preceding statement of object during normal

operation, an arrangement effective at will to condition the governor valve for use in maintaining the pump discharge pressure at a pre-selected value whenever the main actuator stops, whether such stoppage results from stalling or from shifting of the main control valve to its "off" position.

Still another object is to provide a hydraulic system embodying a novel safety arrangement for disabling the normal controls in the event an actuator stalls and in such manner that the supply of fluid to the system must thereafter be stopped before the actuator can be restarted.

Further objects and advantages of the invention will become apparent as the following description proceeds, taken in connection with the accompanying drawing, in which:

Figure 1 is a generally schematic representation of a hydraulic system embodying the present invention.

Fig. 2 is similar to Fig. 1, but shows a modified form of hydraulic system also embodying the present invention.

While the invention is susceptible of various modifications and alternative constructions, I have shown in the drawings and will herein describe in detail certain preferred embodiments, but it is to be understood that I do not thereby intend to limit the invention to the specific forms disclosed, but intend to cover all modifications and alternative constructions falling within the spirit and scope of the invention as expressed in the appended claims.

Referring more particularly to the embodiment of the invention illustrated in Fig. 1, the system there shown comprises a pump 10 as a source of pressure fluid, such as oil. This pump is desirably arranged to deliver fluid at a substantially constant volumetric rate and may be of either the well-known vane type or gear type. Fluid from the pump is delivered, under the control of a main valve 11, to a main actuator 12 consisting of a cylinder 13 and piston 14. Such actuator may drive any movable element desired, and in the present instance it is contemplated that the cylinder 13 be stationary, the piston 14 being shown as rigidly connected to a movable machine tool table 15.

The main valve 11 may take various forms. In the particular construction illustrated, it serves not only to control the stopping and starting of the actuator 12 but also its direction of movement. The valve shown is of the sliding plunger type and comprises a plunger 16 slidable endwise within a suitably ported housing 17. At the

center of the plunger 16 are two lands or collars 18, 19 separated by an annular channel 20, while at the opposite sides of these two central collars are two further collars 21 and 22 separated from the adjacent central collars by respective annular channels 23, 24. Annular end channels 25, 26 separate the collars 21, 22, respectively, from the end portions of the plunger 16. Pressure fluid is delivered by the pump 10 into its discharge or outlet line or conduit 27 from which it passes through branch conduits 28, 29 and 30 so that fluid from the pump is supplied to the main valve 11 through ports at the spaced termini of the three conduits 27, 29 and 30.

Opposite ends of the actuator cylinder 13 are connected to the main valve 11 at spaced points through conduits 31, 32, while a return or exhaust line 33 to the reservoir 34 is connected to the bore of the main valve through three spaced passages or branches 35, 36 and 37.

When the main valve plunger 16 is in the neutral or "off" position shown, midway in its path of travel, the flow of fluid to the actuator 12 is blocked by collars 21, 22 and the fluid discharged from the pump flows through conduits 27, 28 and 30, thence through the central channel 20 in the valve, and through the passage 35 into the exhaust line 33, through which it returns to the reservoir 34. The inlet 38 of the pump 10 is also connected to this reservoir.

Upon shifting the main valve plunger 16 to the right a distance substantially equal to the width of the land 22, pressure fluid discharged from the pump 10 is supplied through conduits 27, 28, 29, and thence through groove 25 and conduit 31 to the left end of the cylinder 13. At the same time, fluid is exhausted from the opposite end of the cylinder through conduit 32 and groove 24, into passage 37 and exhaust line 33 so that the piston 14 moves to the right. Conversely, when the valve plunger 16 is shifted to the left from its mid position shown, pressure fluid is supplied to the righthand end of the cylinder 13 (through 27, 26 and 32), while fluid is exhausted from the lefthand end of the cylinder 13 (through 31, 23, 36 and 33) so that the piston 14 moves in the opposite direction, that is, to the left. The collar 18 or 19, as the case may be, blocks the passage 35 upon shifting of the valve plunger 16 to either right or left. If desired, a back pressure valve 39 of conventional spring loaded type may be interposed in the exhaust line to the reservoir.

The speed of the actuator 12 in either direction of movement is controlled by an adjustable restricted orifice 40 operating in conjunction with a governor valve 41. The restricted orifice 40 is interposed in the exhaust or return line 33 from the actuator and meters the fluid out of the actuator during either forward or reverse movement of the latter. The governor valve 41, on the other hand, comprises a valve plunger 42 having an annular channel 44 therein and slideable endwise within a casing 43. A diversion or bleed passage 45 leads to the governor valve 41 from the pressure line 28 and connection to the exhaust line 33 is completed through a passage 46. A compression spring 47 yieldably biases the valve element 42 toward a position in which it blocks connection between the passages 45, 46. Upon application of sufficient pressure to the left end of the valve element 42, it is shifted to the right against the bias of the spring 47 for connection of the passages 45, 46 through the channel 44, such connection between the passages 45,

46 becoming less and less restricted by the governor valve as the latter is shifted progressively to the right. To subject the valve element 42 to the pressure drop across the restricted orifice 40, a connection is established from the exhaust line 33 on the upstream side of the orifice 40 through conduit 48 having a restriction 49 therein, an annular passage 50 in a pilot valve 51, whose purpose will later appear, and a passage 52.

With the orifice and governor valve 40, 41 arranged as described, any tendency of the actuator 12 to slow down will result in a diminution in the flow of fluid through the orifice 40 and consequent drop in pressure across the same. This will cause the governor valve element 42 to shift to the left under the urge of the spring 47, thereby tending to diminish the amount of the fluid diverted through lines 45, 46, so that the delivery of fluid from the pump to the actuator is correspondingly increased, thus increasing the actuator speed. Conversely, if the actuator 12 tends to over-speed, the amount of fluid exhausted from it will tend to increase so that the pressure drop through the orifice 40 is correspondingly increased and the governor valve element 42 thus shifted to the right to divert a correspondingly increased amount of fluid from the pressure line 28. This results in a slowing down of the actuator by reason of the diversion of fluid which would otherwise pass through it. In this manner the speed of the actuator is precisely and accurately governed with a high degree of sensitivity despite fluctuations of load which may be encountered.

In the system as so far described, when the valve 11 is in its neutral position shown, fluid from the pump 10 is circulated back to the reservoir 34 with substantially no restriction to flow except that offered by the orifice 40 and the small amount caused by the back pressure valve 39. In the event that the governor valve 41 is made sensitive through the use of a light spring 47, as is desirable for maximum sensitivity in its governing operation, the pressure drop across the restricted orifice 40 will be quite small. In such circumstances, the pressure at the pump outlet 27 will fall to a low value when the main valve 11 is shifted to neutral. Although such diminution in pump discharge pressure is desirable from the standpoint of minimizing power consumption for the pump while the main actuator 12 is idle, it may in some circumstances be highly undesirable as, for example, when a branch line 53 is led off the pressure line 27 for supplying various auxiliary devices (not shown). By way of specific example, there may, in a machine tool, be various fixtures, clamps or the like which are arranged to be actuated by fluid pressure derived through the line 53. In such case, it may be requisite that fluid pressure be available in the branch line 53 at a predetermined fixed value at some times for operation of the auxiliaries, while at other times when the auxiliaries are not in use efficiency is best served by permitting the discharge pressure of the pump to fall to a low value.

In accordance with one aspect of the present invention, provision is made for selectively conditioning the system to maintain, at the option of the operator, either a relatively high predetermined pump discharge pressure or to drop such pressure to a negligible value when the main valve 11 is in neutral. It is for this purpose that a hand operated selector valve 54 and the pilot valve 51 are included in the system.

The general function of the selector valve 54 is to disestablish or block the substantially free flow of fluid discharged from the pump back to the reservoir through only the slight restriction of the orifice 40. On the other hand, the general function of the pilot valve 51, in the system illustrated in Fig. 1, is to cut off the connection of the governor valve 41 through the passage 48 to the upstream side of the orifice 40, and to connect the governor valve directly to the discharge side of the pump through lines 52 and 28 when the selector valve 54 is thrown to its closed position.

The pilot valve 51 comprises a plunger 55 having therein the annular channel 50 noted, such plunger being urged by a compression spring 56 into the position shown in which the channel 50 interconnects the lines 48 and 52. The pump discharge pressure is applied directly to the righthand end of the plunger 55 from the line 28.

When the selector valve 54, which is a two-position on-off valve, is shifted from its open position shown to its optionally available closed position, it blocks the flow of fluid from the outlet of the pump into the exhaust line 33. In consequence, pressure builds up on the discharge side of the pump 10 until it reaches a value sufficiently high to overcome the spring 56 and thrust the pilot valve plunger 55 to the left. Such leftward shift of the pilot valve plunger blocks the line 48 and opens communication between lines 28 and 52. The resultant application of pressure to the left end of the governor valve plunger 42 shifts the latter to the right so that fluid is diverted from the pump outlet through passages 45, 46. In this way fluid is diverted from the outlet of the pump through the governor valve but at a pressure determined by the spring setting of the pilot valve 51. By adjustment of the spring loading for the pilot valve, discharge pressure of the pump 10 may thus be maintained at any desired value suitable for actuation of auxiliaries or the like connected to line 53.

It will be observed that in utilizing the arrangement described above, the selector valve 54 may be thrown to its blocking position at any time, as, for example, while the actuator 12 is in motion, without in any way interfering with the normal operation of the governor valve 41 in maintaining a constant feed rate for the actuator. When the main valve 11 is either in its normal right or lefthand position for movement of the actuator 12, the passage 35 is blocked anyhow so that the opening or closing of the selector valve 54 will have no immediate effect on the operation of the system so long as the actuator continues to move normally. Closing of the selector valve at such time does, however, preliminarily condition the system so that upon subsequent stopping of the actuator 12, either by stalling or restoration of the main valve 11 to neutral, the pilot valve 51 will immediately become effective to control the opening of the governor valve for maintaining a predetermined high pressure in the pump discharge line. Should the actuator 12 stall while the selector valve 54 is closed, the governor valve 41 will tend to close since there is no further pressure drop across the orifice 40, and pressure will build up in the pump discharge line. Such pressure tends to shove the actuator ahead to overcome whatever obstruction caused it to stall. The pump discharge pressure is, however, limited to a safe value by the pilot valve 51 for as soon as the discharge pressure reaches the value for which the

pilot valve is set the latter opens, thereby in turn opening the governor valve to divert fluid, so that the pump pressure is limited to the value predetermined by the spring loading of the pilot valve. Such safe pressure, and no more, is thus applied to move the stalled actuator.

From the foregoing, it will be seen that by merely throwing the selector valve 54, the system can be conditioned at will either to cause the pump 10 to continue to deliver fluid at high pressure for use in auxiliaries or the like when the main valve 11 is in neutral, or alternatively conditioned to cause the pump output to be recirculated at low pressure with consequent low power consumption in the event that there is no occasion to use any output pressure from it when the main valve is in neutral. Moreover, in either position of the selector valve 54, safely limited limited pressure is available to break loose the jam should the actuator stall.

By way of analysis, it will be noted that there are in effect first and second alternatively available relief passages from the outlet of the pump when the main valve 11 is in neutral. One such passage returns to the reservoir 34 by way of the exhaust line 33 and the other by way of the governor valve under the control of the pilot valve. Closing the selector valve 54 cuts off the first-mentioned passage by way of the exhaust line and compels the fluid to go through the other passage by way of the governor valve which is controlled by the pilot valve to maintain the desired high pressure.

In Fig. 2 is shown a modified hydraulic system 35 also embodying the present invention. The system of Fig. 2 differs in a structural sense from that of Fig. 1 primarily in that the pilot valve 51a, corresponding to the pilot valve 51, is adapted to cut off positively the flow of fluid to the restricted orifice 40, in addition to performing the other functions noted for the pilot valve 51 heretofore described, whenever the pump discharge pressure builds up sufficiently to actuate the pilot valve. In an operational sense, this results in substantially different characteristics than those heretofore described when the main actuator 12 is stalled, all as detailed below. Since the remaining parts of the system are identical with those employed in the system shown in Fig. 1, the same reference numerals have been used for their identification, and a repetition of the detailed description of the same is unnecessary.

In this instance, the pilot valve 51a has a slideable plunger 55a with two annular channels therein, 50a and 50b, the plunger being urged to the right as before by the compression spring 56. In this instance, the channel 50b is interposed in the exhaust line 33 on the upstream side of the restricted orifice 40, while the channel 50a is interposed between a branch line 33a from the exhaust line 33 and the passage 52 leading to the governor valve 41. In consequence, when the pilot valve plunger 55a is shifted to the left under the influence of pressure on the discharge side of the pump 10, it cuts off any flow of exhaust fluid from the line 33 into the restricted orifice 40, as well as interrupting the flow of fluid from the line 33 to the governor valve and connecting the latter to the pump discharge pressure.

When the actuator 12 is moving normally, the restricted orifice 40 and governor valve 41 coact to govern its speed in precisely the same manner as described with reference to Fig. 1, irrespective of the position of the selector valve 54.

Similarly, when the actuator 12 is stopped by shift of the main valve 11 to neutral, fluid will be circulated from the outlet of the pump back to the reservoir 34 with only the small restriction of the orifice 40 in the event that the selector valve 54 is in the open position shown. On the other hand, if the selector 54 is closed, when the main valve is shifted to neutral, the pilot valve 51a will subject the governor valve 41 to the pump discharge pressure and maintain such discharge pressure at the value determined by the setting of the spring 56 of the pilot valve, also just as in the case of the system shown in Fig. 1.

The difference in operation between the systems of Figs. 1 and 2 occurs when the actuator 12 is stalled with the selector valve 54 closed. As has heretofore been described in connection with Fig. 1, stalling of the actuator 12 when employing the latter system causes the pilot valve 51 to render the governor valve 41 operative to divert fluid from the pump outlet in such manner as to maintain the pump discharge pressure at a safe value determined by the setting of the bias spring 56 of the pilot valve. In contrast, the arrangement in Fig. 2 is such that when the actuator 12 is stalled with the selector valve 54 closed, the pressure on the actuator piston 14 will be equalized and the actuator cannot be restarted until the pump 10 has been stopped and the pilot valve 51a permitted to return to its position shown in the drawings. Since the operator is thus compelled to give special attention to the machine by stopping the pump in the event that the actuator becomes stalled, the safety of the system is obviously enhanced.

Choice of the arrangement of Fig. 1 or Fig. 2 will depend upon whether the particular machine in which the system is installed makes it more desirable to provide the safety stoppage arrangement of Fig. 2 when the actuator stalls, or the continued application of limited pressure as in Fig. 1 to free the actuator under like condition.

As to just what takes place in the system of Fig. 2 when the actuator 12 stalls while the selector 54 is closed, it will be observed that in such case the pressure will build up in the pump discharge lines 27, 28 due to the immobility of the actuator piston 14. In consequence, the pilot valve plunger 55a is shifted to the left, thereby blocking the flow of fluid from the exhaust line 33 to the restricted orifice 40, as well as to the governor valve 41, and at the same time subjecting the governor valve 41 to the pump discharge pressure. Under such circumstances, the pressure on opposite sides of the actuator piston 14 is very quickly equalized and the pump discharge pressure is limited to, and maintained at, a value determined by the setting of the pilot valve spring 56. Once the pilot valve 51a has thus shifted, any subsequent shift of either the main valve 11 or selector valve 54 will be ineffective to change the pressure conditions within the system, wherefore the actuator 12 remains at rest. To again set the system in operation, it is necessary that the operator stop the pump 10 and thereby drop the pump discharge pressure to a value such that the pilot valve 51a is restored to its initial position shown in Fig. 2. The operator is thus compelled to give his attention to the machine and is apprised of the fact that the actuator has been stalled so that he may clear the obstruction which caused the stalling.

I claim as my invention:

1. In a hydraulic system, the combination of a substantially constant volume pump, an ac-

tuator having an inlet and an outlet, means for directing fluid from the pump to said actuator inlet, a restricted orifice interposed in the path of fluid exhausting from the actuator outlet, 5 means defining a fluid diversion passage from the discharge side of the pump, a movable governor valve member interposed in said diversion passage and spring biased into a position to block the same, means for applying to said governor valve member the pressure across said orifice in a direction to oppose said spring bias, and means including a pilot valve for interrupting the application to said governor valve member of the pressure across said orifice and applying to said governor valve member the discharge pressure of said pump, said pilot valve including a spring loaded valve member subjected to the discharge pressure of said pump.

2. In a hydraulic system, the combination of 20 a substantially constant volume pump, an actuator having an inlet and an outlet, means including a main valve having on and off positions in which it respectively directs fluid from the pump to said actuator inlet and to exhaust, a restricted orifice interposed in the path of fluid exhausting from the actuator outlet, means defining a fluid diversion passage from the discharge side of the pump, a movable governor valve member interposed in said diversion passage and 25 spring biased into a position to block the same, means for applying to said governor valve member the pressure across said orifice in a direction to oppose said spring bias, means including a pilot valve operable upon shifting thereof from 30 a first to a second position to interrupt the application to said governor valve member of the pressure across said orifice and to apply to said governor valve member the discharge pressure of said pump, said pilot valve being spring urged to said first position, means for applying the discharge pressure of the pump to said pilot valve in a direction urging it toward said second position, and a selector valve for optionally blocking or opening the flow of fluid from the main valve 35 to exhaust when the latter is in said off position therefor.

3. In a hydraulic system, the combination of a substantially constant volume pump, an actuator having an inlet and an outlet, means for directing fluid from the pump to said actuator inlet, a restricted orifice interposed in the path of fluid exhausting from the actuator outlet, means defining a fluid diversion passage from the discharge side of the pump, a movable valve member interposed in said diversion passage and spring biased into a position to block the same, means for applying to said valve the pressure across said orifice in a direction to oppose said spring bias, and means for interrupting the application to said valve member of the pressure across said orifice and applying to said valve member the discharge pressure of said pump.

4. In a hydraulic system, the combination of 60 a fluid delivery pump and an actuator, a main valve for cutting off the flow of fluid from said pump to said actuator when the valve is in an off position therefor, means including a pressure operated valve for maintaining the discharge pressure of the pump at a predetermined value, and selector means operable only when said main valve is in its off position to render said first mentioned means operative or inoperative at will.

5. In a hydraulic system, the combination of 65 a fluid delivery pump and an actuator, a main valve for cutting off the flow of fluid from said

9 pump to said actuator when the valve is in an off position therefor, and means operable only when the main valve is in said off position to retain the pump discharge pressure either high or low.

6. In a hydraulic system, the combination of a substantially constant volume pump, an actuator having an inlet and an outlet, means for directing fluid from the pump to said actuator inlet, an exhaust line leading from said actuator outlet and having a restricted orifice interposed therein, means defining a fluid diversion passage leading from the discharge side of said pump, a movable governor valve member interposed in said diversion passage and spring biased into position to restrict the same, and means including a pilot valve operable in alternate first and second positions thereof to apply respectively the pressure across said orifice and the pump discharge pressure to said governor valve member in a direction such as to urge the same in each case toward open position against said spring bias, said pilot valve being adapted when in said second position thereof to block said exhaust line on the upstream side of said orifice.

7. In a hydraulic system, the combination of a substantially constant volume pump, an actuator having an inlet and an outlet, an exhaust line leading from said actuator outlet and having a restricted orifice interposed therein, means including a main valve operable in alternate positions thereof to direct the flow of fluid from the pump to said actuator inlet or to block such inlet and direct the pump discharge to said exhaust line, means defining a fluid diversion passage leading from the discharge side of said pump, a movable governor valve member interposed in said diversion passage and spring biased into position to restrict the same, means including a pilot valve operable in alternate first and second positions thereof to apply respectively the pressure across said orifice and the pump discharge pressure to said governor valve member and in each case in a direction to urge said governor valve member toward open position against said spring bias, said pilot valve being adapted when in said second position thereof to block said exhaust line on the upstream side of said orifice, and means including a selector valve operable at will to prevent the diversion of fluid by said main valve into said exhaust line.

8. In a hydraulic system, the combination of a substantially constant volume pump, an actuator having an inlet and an outlet, means for directing fluid from the pump to said actuator inlet, a restricted orifice interposed in the path of fluid exhausting from the actuator outlet, means defining a fluid diversion passage leading from the discharge side of said pump, a movable valve member interposed in said diversion passage and spring biased into a position to restrict the same, means for applying to said valve the pressure across said orifice in a direction to oppose said spring bias, and means for substantially simultaneously interrupting not only the exhaust of fluid from said actuator to said orifice, but also the application to said valve member of the pressure across said orifice and for applying to said

valve member the discharge pressure of said pump.

9. In a hydraulic system, the combination with an actuator and means including a pump for supplying pressure fluid thereto, of means operable automatically upon stalling of the actuator for not only preventing the supply of further fluid to the actuator from said pump but for also thereafter retaining said actuator at rest until the pump has been stopped and restarted.

10. In a hydraulic system, the combination with an actuator and means including a pump for supplying pressure fluid thereto, of means including a valve operable in response to discharge pressure of the pump for effecting the diversion of fluid from the pump outlet to disable the actuator against further movement when the pump discharge pressure reaches a predetermined maximum value and for simultaneously blocking the discharge of fluid from said actuator.

11. In a hydraulic system, the combination with an actuator and a source of pressure fluid therefor, of means operable in response to the application of a predetermined maximum pressure to said actuator for thereafter automatically maintaining a substantially equalized pressure across the actuator to prevent its further movement until the delivery of pressure fluid from said source is stopped.

12. In a hydraulic system, the combination of a fluid delivery pump and a reversible actuator, a conduit having branches, an exhaust line having branches, a main valve shiftable to at least three selectively available positions therefor in two of which said pump is connected to said actuator for movement of the latter in corresponding opposite directions and in the third of which said positions said pump is disconnected from said actuator and connected to a branch of said exhaust line through a branch of said conduit, means including a pressure operated valve for maintaining the discharge pressure of said pump at a predetermined value, means for utilizing pressure in said conduit for rendering said pressure operated valve effective to maintain the pump discharge pressure at said predetermined value when sufficient pressure is made available in said conduit by shift of said main valve to said third position, and a selector valve located in said branch of said exhaust line and connected when said main valve is in said third position to a branch of said conduit for optionally rendering said pressure operated valve effective or ineffective by retaining pressure in or releasing pressure from said conduit.
